UNITED STATES PATENT OFFICE.

FRANK HUMPHRIS, OF PARKSTONE, ENGLAND, ASSIGNOR OF ONE-HALF TO KENNETH ALEXANDER ROBERTS, OF LONDON, ENGLAND.

MACHINE FOR FORGING NAILS OR OTHER ARTICLES.

Application filed December 12, 1922. Serial No. 606,495.

To all whom it may concern:

Be it known that I, FRANK HUMPHRIS, a subject of the King of Great Britain, residing at Parkstone, England, have invented 5 new and useful Improvements in and Relating to Machines for Forging Nails or Other Articles, of which the following is a specification.

This invention relates to machines for 10 forging nails or like articles especially horse-shoe nails.

In nail-machines in which the shank-part of the nail is rolled, hammered, or drawn-out from the full-sized stock in a semi-cold 15 state, the shank of the nail is unduly hardened, becomes excessively rigid and loses its ductility.

The machine according to this invention as applied to the production of horseshoe- 20 nails, or the like, comprises feed-die rolls, a molten metal stock-immersion-bath, a mechanical-depressor to immerse the stock in said molten metal, a set of adjustably and rotatably mounted straightening-rolls, a 25 heating or reheating-chamber through which the stock passes on its way to product-rough-forming-rolls, product-forming-dies and out-cutting punches and dies by which the finished product is separated from the stock 30 and is passed out of the machine. The stock can thus be operated upon while heated to a forging or other desired temperature.

In the accompanying drawing:

Figure 1 is an elevation of a machine constructed according to this invention wherein parts are shown in vertical section.

Figure 2 is a plan-view of the machine.

Figure 3 is a side view of a piece of stock as it appears after passing through one pair 40 of stock-shaping-rolls.

Figure 4 is an edge view of a piece of stock after being passed through the product-forming-rolls comprised in the improved machine.

Figure 5 is a part perspective view of a piece of stock after it has been operated upon in the press-mechanism of the machine by product-forming-dies.

Figure 6 is a vertical section of portions 50 of the opposed feed die rolls.

Like letters of reference refer to like parts throughout the drawings.

In the machine, the subject of this invention there is provided and suitably mounted 55 in a frame *p*, feed die-rolls *b*, a wheel de-

pressor *e*, and guide rollers *f*, a heat-bath *d'* containing molten metal *d*, a set of straightening-rolls *g*, a re-heating muffle *h* with its burners *h¹* and baffle-plate *h²*, a pair or set of product rough-forming-and-feed-rolls *k*, 60 a power-press *m* provided with a ram *o* and a bolster *m¹* on which ram *o* forming punches *l*, blanking-punches *n* and one blade *o¹* of a shear are affixed, and on which bolster *m¹* forming-dies *l¹*, blanking-dies *n¹* and the 65 other blade *o²* of a shear are affixed; the whole mechanical movements thereof being connected by suitable toothed or other gearing *r*, and timed by intermittent gearing *s* to cooperate in the required manner for converting stock into finished nails or other articles and delivering them into a discharge chute *n²* and if desired the fin *a²* formed during their manufacture in sheared-off pieces into a separate discharge-chute *o³*. 75

The feed die rolls *b* provided with grooves *b¹* and recesses or indentations *b²* produce a number of waists *a¹* or parts with a reduced girth in the stock *a* which in the molten lead *d* or its equivalent is raised to a red-hot or 80 nearly red-hot state while guided by the de-pressor *e* in conjunction with rollers *f*.

The stock *a*, after passing through the rolls *g*, is progressively passed and guided into a reheating muffle or chamber *h* which 85 raises the stock *a* up to the desired heat for forging; after which the stock is constrained to pass through intermittently-driven rough-forming and feed-rolls *k* provided with indentations *k¹* of such shape, size and form, 90 as to impart to the irregular cross-sectional shapes of the stock *a* obtained thereon during its passage through the product rough-forming and feed-rolls *k*, any further desired variation thereof, and these heated 95 feed-rolls *k* which obtain their heat from the hot stock *a* passing therethrough and/or by separate burners operating thereon and not shown deliver said stock *a* in its intensely heated condition between forging and forming-punches *l* and forging and forming-dies *l¹* which give the required form to the stock *a*, but leave a fin *a²* about midway of 100 its cross-section, surrounding the product longitudinally. After this forging and forming operation the stock *a*, constrained by the feed-rolls *k*, is progressively carried forward and a second forging and forming operation takes place directly behind the first or other. At the same time the first 105 110

forged and formed part of the stock a with the surrounding fin a^2 is brought so as to register with and come under the action of a blanking-punch n and die n^1 and the punch n presses the stock a through said die n^1 as an outcutting or nail c from its surrounding fin a^2 and at the same time discharges said nail c from its die n^1 into a chute n^2 , but leaves the flash or fin a^2 still attached to the stock a . At the next co-operating set of operations, the perforated part or fin a^2 of the stock a thus left may be wound upon a reel or it may be cut off by shear-blades o^1 and o^2 arranged in a suitable position to do this.

As the stock a is lengthened during its passage between the stock-spacing drawing and compression-rolls b and again during its passage between the product-rough-forming and feed-rolls k the peripheral speed of these rolls b and k is regulated by the gearing r to conform to the variations of length exist-

ing in the stock a so that the waists a^1 thereon will register correctly in the indentations k^1 in the rolls k .

The machine is power driven in the usual way through the medium of a flywheel t and its concomitants.

What I claim is:—

A follow-on-process machine embodying intermittently-rotated feed die-rolls, a heat-bath of molten metal, a depressor associated with said heat bath, a set of stock-straightening-rolls, a stock re-heating muffle and baffle, a set of intermittently-rotated combined product-rough-forming and feed-rolls, a power-press comprising a ram and a bolster, product-forming-punches, blanking-punches and one blade of a shear carried by said ram, and product-forming-dies, blanking-dies and the other blade of a shear carried by said bolster.

FRANK HUMPHRIS.
